UNITED STATES PATENT OFFICE.

MATHIAS WILBERT, OF PHILADELPHIA, PENNSYLVANIA, ASSIGNOR OF ONE-HALF TO
ALEXANDER CLARK, OF PHILADELPHIA, PENNSYLVANIA.

WINDOW LOCK.

Application filed August 22, 1922. Serial No. 583,517.

This invention relates to sash locks for windows, and the object of the invention is to provide an automatic sash fastener of simple construction which will not only lock the sashes in closed position, but will lock the sashes of opened windows against further opening from the outside.

These objects, and other advantageous ends which will be described hereinafter, I attain in the following manner, reference being had to the accompanying drawings in which—

Figure 1 is a fragmentary inside elevation of a window equipped with the improved automatic window lock,

Figure 2 is an enlarged fragmentary vertical sectional view taken on the line 2—2 of Figure 1,

Figure 3 is a view similar to Figure 2 showing the sashes partly opened,

Figure 4 is a face view of a ratchet strip forming a part of the device,

Figure 5 is a sectional view taken on the line 5—5 of Figure 4,

Figure 6 is a plan view of a detent device forming part of the lock,

Figure 7 is a sectional view taken on the line 7—7 of Figure 6,

Figure 8 is a sectional view taken on the line 8—8 of Figure 6, and

Figure 9 is a plan view of a blank from which a bracket forming a part of the device, is made.

In the drawings, 9 designates a window frame in which an upper sash 10 and a lower sash 11 are slidable. The window lock includes a flat metallic plate 12 having apertures 13 near its ends for securing it to the inner face of one side and above the bottom rail of the upper sash. Plate 12 has a series of spaced stops 14 pressed therefrom to provide ratchet teeth having their engaging faces at the bottom.

A detent device co-operates with plate 12 and consists of a detent 15 pivoted, near one end in a U-shaped bracket 16 secured to the top rail of the lower sash. The ends 17 and 18, of the detent are beveled in opposite directions. End 17 is adapted to engage with the ratchet teeth and lock the upper sash against downward movement relatively to the lower sash and the lower sash against upward movement relatively to the upper sash. End 18 is beveled sufficiently to allow

the detent to be swung out of engaging position. Detent 15 is preferably provided with an aperture 19 in such position that, when the detent is in locking position, it will be partly covered by the ears of bracket 16 and, when the detent is swung out of engaging position, it will be uncovered. The detent may then be held in idle position by inserting a pin 20 in aperture 19.

Bracket 16 may be made from sheet metal by stamping out an oblong plate with apertures 21 near its ends, two U-shaped cuts 22 forming tongues extending from either side of a central cross bar 23 and apertures 24 in the tongues, then bending the tongues up to form the ears of the bracket.

With the window closed and the detent in engaging position, as shown in Figure 2 of the drawing, the detent will be in engagement with the lower ratchet tooth and will hold both sashes against opening movement.

Withdrawing the detent permits either sash to be opened to any desired extent and by allowing the detent to engage a ratchet tooth the sashes will then be held against relative opening movement. If, for example, the upper sash is lowered four inches it cannot be further lowered but the lower sash may be raised thereby forcing the upper sash upward thereby closing the four inch opening at the top and leaving a four inch opening at the bottom. Likewise, if the upper sash be lowered two inches and the lower sash raised two inches, both sashes may be raised thereby closing the top opening and leaving a four inch opening at the bottom, or both sashes may be lowered thereby closing the opening at the bottom, but always maintaining the four inch limit and precluding entry of an intruder.

When the detent is in engaging position an open sash may be closed, the detent riding over the inclined faces of the ratchet teeth and falling by gravity into locking position.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what

I claim as new and desire to secure by Letters Patent is:—

1. A window sash fastener consisting of a ratchet plate adapted to be secured to the upper sash and having a central row of teeth cut and pressed outward therefrom; a bracket adapted to be secured to the top of the lower sash; said bracket having spaced ears; a detent plate pivotally mounted in the bracket and having a bevelled end adapted to engage beneath the teeth of said ratchet plate, said detent having an aperture partially concealed when in operative position and exposed when in inoperative position; and a pin closely fitting in and removably projected through said aperture when in exposed position for holding the detent in its inoperative position.

2. A window sash fastener consisting of a ratchet plate adapted to be secured to the upper sash; a bracket adapted to be secured to the top of the lower sash, said bracket consisting of a plate having tongues cut and bent up therefrom to form spaced ears; a detent bar with a bevelled end pivotally mounted between said ears and adapted with its other end to engage said ratchet plate, said detent having an aperture that

is exposed when in inoperative position and partly concealed when in its operative position; and a pin closely fitting and removably projected through said aperture when in its exposed position and bearing on said ears for holding the detent in inoperative position.

3. A window sash fastener consisting of a ratchet plate adapted to be secured to the upper sash and having a central row of teeth cut and pressed outward therefrom; a bracket adapted to be secured to the top of the lower sash, said bracket consisting of a plate having tongues cut and bent up therefrom to form spaced ears; a flat detent plate with bevelled ends pivotally mounted between said ears and adapted to engage beneath the teeth of said ratchet plate, said detent having a small aperture; and a pin closely but removably fitting in and projecting through said aperture when in a fully exposed position and bearing on said ears for holding the detent in its inoperative position.

In testimony whereof I have signed my name to this specification.

MATHIAS WILBERT.
